BOWL LINER FOR GYRATORY CRUSHER

Loren G. Symons, North Hollywood, Calif., assignor to Nordberg Manufacturing Company, Milwaukee, Wis., a corporation of Wisconsin
Original application Nov. 14, 1961, Ser. No. 152,221, now Patent No. 3,140,834, dated July 14, 1964. Divided and this application Oct. 5, 1962, Ser. No. 228,533
12 Claims. (Cl. 241—299)

This is a division of Serial No. 152,221, filed November 14, 1961, now U.S. Patent No. 3,140,834, issued July 14, 1964.

This invention is in the field of material reduction machines and is concerned, among other things, with an improved gyratory crusher.

A primary object of the invention is an improved gyratory crusher which is efficient in use.

Another object is an improved bowl liner for a gyratory crusher.

Another object is an improved locking arrangement for the bowl liner of a gyratory crusher.

Another object is improved wearing parts for a gyratory crusher.

Another object is a flexible system for varying the crushing cavity contours of a gyratory crusher.

Other objects will appear from time to time in the ensuing specification and drawings in which:

FIGURE 1 is a vertical section of a gyratory crusher; FIGURE 2 is a portion of FIGURE 1, on an enlarged scale;

FIGURE 3 is a portion of FIGURE 1, on an enlarged scale, partially in full; and

FIGURE 4 is a top view of the liner, partially shown in FIGURE 3.

In FIGURE 1, a crusher has been shown generally including the following main parts, a main frame A which supports a bowl structure B releasably held on the main frame by a release mechanism C and arranged to be adjusted by an adjustment mechanism D. The main frame also supports a crushing head E defining a crushing cavity with the bowl.

The main frame A includes a base flange 10 with an upstanding housing 12 and a supporting flange 14 for the bowl structure at the upper end.

The bowl structure B may include an adjustment or tilting ring 100 screw threaded as at 102 to a bowl 104. As shown in FIGURE 2, the adjustment ring rests on and is supported by an upstanding annular flange 106 on the main frame with the two having opposed upwardly and inwardly directed or convergent contacting or abutting surfaces 108 which constitute the sole support or contact between the bowl structure and frame.

The bowl proper is provided with a generally cylindrical outer portion 128 which has a threaded exterior and an inner somewhat frusto-conic portion 130 which rises and terminates in an annular shoulder or ledge 132. The ledge supports an annular insert 134 which may be removably welded both to the shoulder 132 and to a back-up portion 136 higher up on the bowl. The insert may be generally L-shaped in cross section, having a trough-like appearance, opening generally upwardly and subdivided by webs or strengthening ribs 138 into a plurality of pockets.

2

A generally frusto-conic liner 140 has a generally continuous outwardly disposed ledge 142 at its upper end, in FIGURE 3. The inner portion 144 of the bowl insert projects inwardly and, in effect, functions as a back-up for the upper portion of the liner. The diameter of the inner portion of the insert is slightly greater than the outer diameter of the ledge 142 on the liner so that the liner may be raised in the bowl in the position shown.

The liner is held in place by a plurality of wedge elements 146, shown in FIGURE 3, each of which may have a crowned forward surface 148 and slide on an annular flat surface 149 on the bowl insert. The wedge is forced radially inwardly under the ledge 142 on the liner by a bolt 150 or the like, which fits in a socket 152 in the insert. A thrust nut 154 on the bolt has a convex forward surface which fits in a corresponding concave surface or socket 155 in the rear of the wedge. Thus, the wedge may be forced inwardly against the liner by turning the thrust nut 154. The contacting surface 148 of the wedge is crowned or arcuate both vertically and horizontally.

As shown in FIGURES 3 and 4, the upper ledge or flange 142 at the top of the liner is formed into a plurality of segments or locking surfaces 156, each of which is helically disposed to the liner axis with a point 156a of maximum downward excursion and swung on an arc eccentric to the liner axis with a point 157 of maximum outward excursion, as shown in FIGURE 4. Six such locking surfaces have been shown, but it should be understood that more or less may be used. The under surfaces of the ledges are arcuate in cross section, at 158, and the return surface 160 between locking surfaces may be swung on a small arc or may be straight. The direction of the helix of each surface 156 is such, relative to the direction of rotation of the head, that the liner tends to tighten itself on the crowned faces of the wedges. The wedges may be differentially forced in against the locking surfaces 156 on the liner until the liner is pulled up firmly against the bowl proper.

FIGURE 4 is a top view of the liner, partially shown in FIGURE 3.

In FIGURE 1, a crusher has been shown generally including the following main parts, a main frame A which supports a bowl structure B releasably held on the main frame by a release mechanism C and arranged to be adjusted by an adjustment mechanism D. The main frame also supports a crushing head E defining a crushing cavity with the bowl.

The main frame A includes a base flange 10 with an upstanding housing 12 and a supporting flange 14 for the bowl structure at the upper end.

The bowl structure B may include an adjustment or tilting ring 100 screw threaded as at 102 to a bowl 104. As shown in FIGURE 2, the adjustment ring rests on and is supported by an upstanding annular flange 106 on the main frame with the two having opposed upwardly and inwardly directed or convergent contacting or abutting surfaces 108 which constitute the sole support or contact between the bowl structure and frame.

The bowl proper is provided with a generally cylindrical outer portion 128 which has a threaded exterior and an inner somewhat frusto-conic portion 130 which rises and terminates in an annular shoulder or ledge 132. The ledge supports an annular insert 134 which may be removably welded both to the shoulder 132 and to a back-up portion 136 higher up on the bowl. The insert may be generally L-shaped in cross section, having a trough-like appearance, opening generally upwardly and subdivided by webs or strengthening ribs 138 into a plurality of pockets.

When the liner 140 is worn out, the thrust nuts 154 can be backed off or the bolts may be torched out. This frees the wedges so that they can be backed off and the liner can be easily removed and replaced.

It will be realized that whereas a practical and operative device has been described and claimed, nevertheless, many changes may be made in the size, shape, number and disposition and relation of parts without departing from the spirit of the invention. It is, therefore, wished that the

FIGURE 1 is a vertical section of a gyratory crusher; FIGURE 2 is a portion of FIGURE 1, on an enlarged scale;

FIGURE 3 is a portion of FIGURE 1, on an enlarged scale, partially in full; and

FIGURE 4 is a top view of the liner, partially shown in FIGURE 3.

In FIGURE 1, a crusher has been shown generally including the following main parts, a main frame A which supports a bowl structure B releasably held on the main frame by a release mechanism C and arranged to be adjusted by an adjustment mechanism D. The main frame also supports a crushing head E defining a crushing cavity with the bowl.

The main frame A includes a base flange 10 with an upstanding housing 12 and a supporting flange 14 for the bowl structure at the upper end.

The bowl structure B may include an adjustment or tilting ring 100 screw threaded as at 102 to a bowl 104. As shown in FIGURE 2, the adjustment ring rests on and is supported by an upstanding annular flange 106 on the main frame with the two having opposed upwardly and inwardly directed or convergent contacting or abutting surfaces 108 which constitute the sole support or contact between the bowl structure and frame.

The bowl proper is provided with a generally cylindrical outer portion 128 which has a threaded exterior and an inner somewhat frusto-conic portion 130 which rises and terminates in an annular shoulder or ledge 132. The ledge supports an annular insert 134 which may be removably welded both to the shoulder 132 and to a back-up portion 136 higher up on the bowl. The insert may be generally L-shaped in cross section, having a trough-like appearance, opening generally upwardly and subdivided by webs or strengthening ribs 138 into a plurality of pockets.

When the liner 140 is worn out, the thrust nuts 154 can be backed off or the bolts may be torched out. This frees the wedges so that they can be backed off and the liner can be easily removed and replaced.

It will be realized that whereas a practical and operative device has been described and claimed, nevertheless, many changes may be made in the size, shape, number and disposition and relation of parts without departing from the spirit of the invention. It is, therefore, wished that the

description and drawings be taken as in a broad sense illustrative or diagrammatic rather than as limiting to the precise showing.

The use, operation and function of the invention are as follows:

The head and bowl carry opposed renewable crushing members, identified as a mantle on the head and a bowl liner on the bowl. These opposed parts define a crushing cavity to receive material fed downwardly and, preferably, inwardly from above. As the eccentrically apertured sleeve rotates, the head is gyrated about the point X of FIGURE 1, and a crushing nip or approach of head to bowl passes around the crushing cavity. The opposed crushing members are subjected to wear and are renewed at various intervals, depending upon the particular material crushed.

With reference to the wearing parts, and particularly to the bowl liner shown in FIGURES 3 and 4, the liner 140 has at its upper edge a continuous, outwardly disposed flange or ledge 142 which serves as a reinforcement for the upper edge of the bowl liner. This reinforcing flange 142, which is continuous, has an outwardly generally continuous lower surface. Since the outer edge of the flange 142 is of a diameter less than the diameter of the inner edge of the bowl insert or adapter, the bowl liner may easily be upwardly inserted from below, and may be downwardly freely removed through the bowl structure when removal is desired. Simple means, however, are provided for holding the bowl liner in position without the use of a complicated structure and without the use of any securing means which can get so packed with material or dust during use as to be difficult of removal. As will be clear from FIGURES 1 and 3, the bowl insert or adapter has a generally plane upper surface. Wedges may be thrust inwardly toward the upper edge of the bowl liner by the thrust nuts. Release of the bowl liner is simple and easy, since all that is necessary is to back off the thrust nuts or cut the bolts 150 with a torch or the like.

The flange 142 at the upper edge of the liner is engaged by the wedges which constitutes support for the liner in the bowl and also makes the liner self-tightening. The lower surface of the flange, as at 156, is formed into a plurality of surfaces, each of which is both eccentrically and helically disposed relative to the direction of gyration of the head of the crusher. The point of maximum downward helical excursion 156a of the flange is slightly above the supporting surface 149 of the bowl insert when the liner is properly positioned in the bowl. The point of maximum outward eccentric excursion, as at 157, lies within the circumferential interior of the supporting surface, as at 170 in FIGURE 3, so that the liner is easily inserted. Thus, the maximum outward excursion 157 of the flange clears the inner edge of the supporting surface 170.

The effect of this combination of the helically and eccentrically disposed flange is that the reactive thrust against the wedge face 148 is at a distinct angle, such as along the broken line 172 in FIGURE 3. This has the advantage that the line of reaction will fall outside of the inner edge of the supporting surface 149. This is to say that the reaction will fall on the supporting surface 149.

I claim:

1. For use with gyratory crushers and the like, a bowl liner and securing assembly therefor which includes a generally frusto-conic body of manganese steel or the like having about its upper edge an outwardly extending reinforcing flange having an outwardly disposed circumferentially extending lower surface formed into a plurality of eccentric steps, and a plurality of wedge segments each being formed to direct a generally radial inward thrust against one of the eccentric steps, whereby to cause an upward thrust against the lower surface of said flange, the individual wedges each having a screw threaded stem and a thrust nut threaded thereon.

2. In a gyratory crusher, a main frame, a bowl mounted in the main frame for adjustment, an insert positioned in the bowl with means for removably supporting a bowl liner against the bowl, the bowl having an upwardly and inwardly extending frusto-conical portion, truncated to terminate in a supporting ledge, the insert being positioned on the ledge and in outward contact thereabove with the bowl, the insert having a troughlike interior, opening inwardly and upwardly, and a plurality of individual pockets formed in the trough to support individual clamping units to removably clamp the liner against the bowl.

3. The structure of claim 2 further characterized by and including cylindrical mating surfaces between the bowl and insert to accurately center the insert in the bowl.

4. In a bowl liner for gyratory crushers and the like, a frusto-conic body having about its upper end an outwardly extending reinforcing flange, the lower outer surface of said flange being formed into a plurality of surfaces, each of which is eccentrically and helically disposed relative to the liner axis such that the liner will tend to be self-tightening on the bowl.

5. A bowl liner for use in gyratory crushers and the like with means for supporting and securing the liner in relation to the bowl thereof with the crusher having a supporting upwardly facing annular surface about the upper end of the bowl liner, the improvement comprising a generally frusto-conic body of manganese steel or the like adapted to be disposed generally upright in such a crusher, small end up, and having an outwardly extending generally continuous flange about its upper end disposed circumferentially about the upper end of the liner and having a generally continuous lower surface, the liner being constructed so that when it is properly positioned in the crusher, the lower surface of the flange will be at a level slightly above the supporting surface of the crusher, the lower surface of the flange being divided into a series of separate surfaces, each of the separate surfaces increasing in excursion both helically and axially in a direction such that the liner will tend to be self-tightening in use,

40 the maximum helical downward excursion of each such surface lying in a plane generally above the supporting surface of the crusher when the liner is properly positioned in the crusher, the maximum outward eccentric excursion of each such surface lying within the circumferential interior of the supporting surface so that the liner may be initially inserted without contacting the interior of the supporting surface, the minimum helical excursion of each such surface lying sufficiently above the supporting surface, when the liner is properly positioned in the crusher, such that each may be contacted by a wedging element 45 mounted for inward radial movement on the supporting surface to hold the liner in place.

6. The structure of claim 5 further characterized in that the lower surface of the flange has an outer edge which is convexly rounded in cross section.

55 7. The structure of claim 5 further characterized in that each of the separate surfaces are separated by individual steps.

8. In a gyratory crusher or the like, a frame, a bowl in the frame, a head mounted for gyratory movement relative to the bowl and defining a crushing cavity therewith, and a bowl liner removably secured on the bowl, the frame having an upwardly facing annular surface above the crushing cavity functioning as a support for the bowl liner, the bowl liner being in the form of a frusto-conic body 60 of manganese steel or the like disposed generally upright, small end up, and having an outwardly extending generally continuous flange about its upper end with a generally continuous lower surface, the liner being positioned in the crusher with the lower surface of the flange slightly above the supporting annular surface of the crusher, the lower surface of the flange being divided into a series of separate surfaces, each of the surfaces increasing in excursion both helically and axially in a direction such that the liner will tend to be self-tightening, the maximum helical downward excursion of each such surface lying in a plane gen-

erally above the supporting surface of the crusher, the maximum outward eccentric excursion of each such surface lying within the circumferential interior of the supporting surface, a plurality of wedge elements mounted for radial movement on the supporting surface constructed to project inwardly to engage the separate surfaces, the minimum helical excursion of each such surface lying sufficiently above the supporting surface, when the liner is in position on the crusher, such that the wedging element contacts it when projected inwardly.

9. The structure of claim 8 further characterized in that each of the wedge elements has a forward face opposite and engageable with the separate surfaces, such face being convex both vertically and horizontally.

10. The structure of claim 8 further characterized in that the separate surfaces are separated by individual steps.

11. The structure of claim 8 further characterized in that the upwardly facing annular surface is a part of an insert positioned in the bowl, the bowl having a lower upwardly and inwardly extending surface terminating in a supporting ledge, the insert being positioned on the ledge and in outward contact thereabove with the bowl.

12. The structure of claim 4 further characterized in that the lower surface of the flange has an outer edge which is convexly rounded in cross section.
